GAS CONTROL VALVE

Filed Feb. 24, 1947

UNITED STATES PATENT OFFICE

2,584,936

GAS CONTROL VALVE

Casper S. Stuckenholz, South Euclid, Ohio, assignor to The W. J. Schoenberger Company, Cleveland, Ohio, a corporation of Ohio

Application February 24, 1947, Serial No. 730,236

6 Claims. (Cl. 251—163)

1

The invention relates to gas control valves adapted particularly for cooking ranges. An object is to provide an improved valve on the order of that shown in Stuckenholz Patent No. 2,262,703; November 11, 1941. The valve shown in that patent has provision for informing the operator through audible signal means when the valve has been turned into certain desired positions such, for example, as "full on," "simmer" and "off" positions. Said valve also has provision for releasably locking the operating stem in the "off" position with the view to discouraging unauthorized tampering with the range controls. The present valve construction provides comparable position-indicating signals and a more economically manufactured means for locking of the operating stem in the "off" position, and also employs a considerably less number of easily formed parts to accomplish the desired functions, thus indicating further objects hereof.

A specific object is to provide an improved gas control valve for cooking ranges, said valve having a low or simmer-cooking flame-adjustment arranged effectually to prevent escape of gas from the valve while the adjustment is being effected.

A further object is to provide an improved gas control valve having a low-flame adjustment capable of manipulation through a hollow valve plug positioning stem.

A further object is to provide a gas control mechanism employing an axially shiftable control-plug-positioning stem cooperating with a locking plate inside the valve assembly and arranged to insure assembly of the valve parts in proper operating relationship only.

A further object is to provide a gas control valve with provision for effecting an audible signal in each of a number of functional positions and locking of the stem in one of said positions, with parts so arranged that they cannot be improperly assembled.

Other objects and features of the invention will become apparent from the following description of the preferred form shown in the accompanying drawing, wherein:

Fig. 1 is a central longitudinal assembly view of the valve mechanism with the main valve plug in "full on" position;

Fig. 2 is a similar view showing the valve in the "off" position;

Fig. 3 is a fragmentary longitudinal sectional view taken as indicated at 3—3 on Fig. 1, parts of the mechanism being omitted in order more clearly to illustrate other parts;

Fig. 4 is an end view of the valve plug; and

Fig. 5 is an exploded view showing the principal movable parts of the assembly.

Referring to Fig. 1, the body 1 of the valve assembly, preferably a casting, is formed with a

2

threaded inlet branch 2 adapted for connection with a gas manifold pipe and having a central passage 2', said body having an externally threaded tubular outlet or discharge portion 3 arranged to support a conventional burner-flow-adjustment sleeve 4 with a restricted central discharge orifice 5. The outlet portion 3 has a central bore, receiving a fluted or non-circular body or shank of a conventionally pointed needle element 6 projecting into the orifice 5. The position of the pointed end of the needle element in the restricted orifice determines the maximum gas flow from the valve assembly to the burner, adjustment being effected as usual.

The body 1 has a conical bore 7 for receiving a main gas control plug 8, spring-seated against the conical bore as described later herein. The plug 8 has a longitudinal passage 9 aligned with the bore of the outlet portion 3 and a lateral main inlet bore 10 arranged for registration with the inlet bore 2' in the position of the plug illustrated in Fig. 1, whereby the burner is supplied with gas at maximum flow rate. That rate can be diminished gradually by partial non-registration of the ports 2' and 10. Additionally, the plug 8 has an axial restricted bore 11 formed as a counterbore of the main outlet passage 9 and which intersects an oblique low-flame-conducting gas passage 14, Figs. 2 and 3, communicating at its outer end with a shallow depression or recess 15 transversely aligned with the inlet passage 2' when the plug 8 is turned, for example, 90° from the full "on" position shown in Fig. 1 to the low-flow or "simmer" position, not shown. In the "simmer" position, gas is enabled to flow to the burner only through the shallow recess 15, the restricted, oblique passage 14, counterbore 11, etc.

At the intersection of the oblique passage 14 and counterbore 11, an adjustable valve plug 17 is provided so that gas for simmer cooking purposes can be very accurately and finely adjusted to the desired low flow value. As shown, the simmer cooking adjustment plug 17 has a threaded shank 16 in and extending from a reduced diameter stem portion 19 of the plug 8, generally coaxial therewith but partially of non-circular cross section for operating connection with a tubular operating stem 20. The plug 17 is adjusted to extend partially into blocking relationship to the oblique passage 14 as shown on Figs. 2 and 3.

The tubular operating stem 20 carries at its outer end a suitable manually adjustable handle 21. Said operating stem has an enlarged generally cylindrical inner end portion 22 (see Fig. 5) having a transverse parallel-sided end slot 23, open axially of said portion 22 and which fits diametrically opposite flat faces 25 and 26 on the stem portion 19 of the plug 8. Said flat faces 25

3

and 26 are located different distances from the axis of the plug 8 and the cooperating faces of the slot 23 are respectively located those same different distances from the axis of the tubular operating stem so that the plug and tubular stem can be axially aligned in only one relatively turned position of said plug and tubular stem. Such axial alignment is necessary in order to complete the assembly as will be further demonstrated below.

The generally cylindrical enlargement or head 22 of the tubular operating stem 20 is contained within a cap sleeve 28 adapted to be threaded onto a generally circular, although not wholly continuous, flange 29 of the body 1 concentric with the taper bore 7. The cap sleeve 28 has an inturned flange 30 against which a locking plate device 31, contained in the sleeve, is secured as shown by Figs. 1, 2 and 3. The locking plate device 31 is, in part, a ring having a D-shaped central opening 32 having a straight edge portion 33. The enlargement or head 22 of the operating stem has one flat side face 34 which, in the "off" position of the valve plug 8 (Fig. 2), registers with the straight edge 33 of the opening 32 to form an "off" position lock for the operating stem as will be described more in detail below. Except in the "off" position, the enlargement 22 of the operating stem is retained axially in the position shown in Fig. 1 by a flat axially directed shoulder 35 defining one end of the enlargement 22. The shoulder 35 abuts the inner face of the locking plate device 31 in all turned positions of the operating stem except the "off" position illustrated by Fig. 3; and in that position, the shoulder 35 and flat face 34 may pass into the D-shaped opening 32 of the locking plate device. Said device 31 as shown (upper right, Fig. 3; lower right, Fig. 5) has a position-retaining flange 41 of arcuate section conforming to the flange 29 of the body 1 and having a T-shaped head, partially shown at 42. The T-shaped head, during assembly of the operating stem 20, sleeve 28 and other parts into place, is seated into a complementary notch 43 (Fig. 3) in the body flange 29. Seating of the T-head 42 into the notch 43 holds the locking plate in properly turned position on the valve body; and if, during assembly, the valve plug 8 and operating stem 20 have been improperly assembled at the notch 23 and faces 25 and 26, it is then impossible to seat the T-head 42 into the notch 43 and then screw the cap 28 onto the valve body.

The enlargement 22 of the operating stem has intermediately of its ends a peripheral rib 36 co-extensive only with the cylindrical portion of the enlargement, and the rib is always in abutment with a flat annular washer 37 having radially disposed notches in pairs at 38 and 39 adjacent the enlargement 22. At one side, the washer 37 has an arcuately extending peripheral indentation 40 in splined relation to the flange 41 of the locking plate device 31 to hold the washer against turning within the sleeve 28, but enabling relative axial motion of the washer and the enlargement 22 of the operating stem.

Cooperating with the notched washer 37 is a signal plate or washer 44 which has a spline (D-connection) with the enlargement 22 of the operating stem formed by a flat edge 45 complementary to the flat face 34 of said enlargement. Otherwise, the opening in the washer 44 slidably fits the cylindrical surface portion of the enlargement 22. At diametrically opposite points, for example perpendicular to the flat edge 45, the

4

washer 44 has oppositely sloping (e. g. triangular) projections 46 arranged to snap into the paired notches 38 and 39 in three different turned positions of the operating stem. The washer 44 has a flange 47 with generally radially extending edges which abut the side edges of the flange 41 of the locking plate device 31 to arrest the turning movement of the operating stem in the "off" and "simmer" positions of the valve plug 8, so that the plug cannot be turned past those positions in respectively opposite directions. In the particular arrangement shown, the flanges 41 and 47 limit the turning movement of the stem to 180°.

The washer 44 is forced against the washer 37 and the latter thereby maintained against the rib 36 by a coiled compression spring 50. One end of the spring seats against the washer 44 and the opposite end against the valve plug 8. The spring thus performs the dual function of maintaining the valve plug seated in its tapered bore 7 while forcing the projections 46 of the signal washer 44 in the proper direction for audible signaling engagement with the paired notches 38 and 39 of the washer 37.

Comparing Figs. 1 and 2, the former shows the stem 20 maintained in a position thrust toward the plug 8, being retained by the locking plate device 31 against outward movement away from the plug, and the latter, Fig. 2, shows the stem 20 turned to a position in which the flat face 34 of said stem aligns with the D-edge 33 of the locking plate device 31, enabling the spring 50 to force the stem 20 outwardly so that the face 34 lies in locking relation to said edge 33, thus holding the stem 20 against being turned until it is moved axially toward the valve plug. When the stem is thrust inwardly toward the valve plug, as to the position shown in Fig. 1, the plug can then be turned first to the full "on" position illustrated by Fig. 1, and then to the "simmer" position in which the flow of gas may be variably restricted by the adjustable plug 16, 17. In each of the main positions: "off," "full on" and "simmer," an audible signal is given when the triangular projections or ribs 46 of the washer 44 snap into one or the other pair of notches 38 and 39 of the washer 37.

The outer end of the hollow operating stem 20 preferably is cut away to provide a D-formation at 55, Fig. 2, (cf. Fig. 5) receiving a complementary inwardly thickened portion 56 in the socket of the handle 21. The handle may be removably secured to the stem by friction, by a suitable spring detent or, as illustrated, by a locking screw 57 threaded as at 58 into said thickened portion. The screw 57 is preferably concealed within a counterbore 59 of the handle, and, as shown, may be forced against the inner wall of the central bore of the operating stem 20.

The "simmer" flow adjusting screw 16 is rendered readily accessible for adjustment when the handle 21 is removed; and, since the removal of the handle prevents manual operation of the valve, the plug will be undisturbed during the making of the adjustment. It is important that the valve plug shall not be accidentally unseated during manipulation of the adjusting screw 16 for otherwise flash-back ignition of gas, leaking from the valve, may occur. Because it is an easy matter to remove the handle and a relatively difficult operation for a novice to reassemble the locking and signal-effecting parts after removal of the threaded cap sleeve 28, operation of the "simmer" adjustment screw 16 otherwise than 75 through the hollow stem following removal of

the handle 21 is not apt to be repeated if done once.

I claim:

1. A gas control valve comprising a body having a circular bore formed with a port, a plug seated in said bore and having lateral flow control passages at an angle to each other about the axis of the bore and a closing land surface, all in the plane of said port, an operating stem in splined relation to the plug, a cap sleeve secured to the body in surrounding relation to the operating stem, a locking plate within the sleeve having a plate-rotation-preventing interlocking connection with the body within the sleeve, which connection includes relatively abutting circumferentially directed shoulders on the body and locking plate which shoulders are maintained in mutual registration by radial juxtaposition of the sleeve and locking plate in the region of the shoulders, and a releasable spline connection between a non-circular central through opening in the locking plate and a non-circular portion of the stem extending through said central opening, said connection operating, in an axially shifted position of the stem, to lock the stem against being turned.

2. A gas control valve comprising a body having a circular bore formed with a port, a plug seated in said bore and having lateral flow control passages at an angle to each other about the axis of the bore and a closing land surface, all in the plane of said port, an operating stem having a head in splined relation to the plug, a cap sleeve removably secured to the body in surrounding relation to said head, a locking plate device within the sleeve and non-turnably connected with the body when the sleeve is secured thereto, the locking plate and stem having a releasable D-connection comprising a D-shaped opening in the plate around the stem engageable with a complementary portion of the stem to secure the stem in one turned position, and mechanism within the sleeve including spring means arranged to arrest the head in said turned position and to shift the head to render the D-connection effective.

3. A gas control valve comprising a body having a tapered bore formed with a port, a tapered plug seated in said bore and having lateral flow control passages at an angle to each other about the axis of the bore and a closing land surface, all in the plane of said port, an operating stem having a head detachably splined to the plug, a cap sleeve threaded to the body in surrounding relation to the head of the operating stem, locking means and audible signal-effecting means within the sleeve and cooperatively related to the head to lock the head in an "off" position of the plug and to effect signaling in "off" and a plurality of "on" positions, and a single spring operating to actuate the signal means, to move the head of the stem axially and render the locking means effective and to maintain the plug seated in its tapered bore.

4. A valve comprising a hollow body and a rotatable plug for controlling inlet or outlet passages of the valve, said plug having a shank portion, said passages including a low-flow passage portion of the plug, an adjustment device supported axially of the shank and arranged for variably restricting the low-flow passage portion, an axially shiftable hollow operating stem telescoping said shank and through which the device is accessible for adjustment, a locking device for

the operating stem supported by said body and having a non-circular aperture through which a non-circular portion of the stem is arranged to extend for locking the stem in one turned and axially shifted position of the stem, the non-circular portion of said stem and the plug shank being relatively arranged so that assembly of the operating stem and plug into concentric relationship is possible in only one relatively turned position of the operating stem and the plug shank.

5. A valve comprising a hollow body and a rotatable plug for controlling inlet or outlet passages of the valve, said plug having a shank portion, said passages including a low-flow passage portion of the plug, an adjustment device supported axially of the shank and arranged for variably restricting the low-flow passage portion, an axially shiftable hollow operating stem telescoping said shank and through which the device is accessible for adjustment, a locking device for the operating stem supported by said body and having a non-circular aperture through which a non-circular portion of the stem is arranged to extend for locking the stem in one turned and axially shifted position of the stem, the non-circular portion of said stem and the plug shank including substantially parallel flat faces located different distances from the axis of the stem and plug, enabling concentric assembly in only one relatively turned position of the stem and plug.

6. In a valve, a body and rotatable control plug with an operating shank formed thereon, an operating stem having an inner enlarged head portion slidably keyed to the stem, said head having a peripheral rib between its ends, two generally circular and centrally apertured signal-effecting plates surrounding the head in superposed relation inwardly from the rib, one of the plates being shouldered against the rib, a compression spring surrounding the head between the plug and innermost plate reacting on the plug to force the plates yieldably together and the operating stem outwardly, a sleeve removably secured to the body around the head and plates, an apertured stop plate through which the stem is slidably guided, said stop plate being held by the sleeve in keyed relationship to the valve body, one of said signal-effecting plates being splined to the head and shouldered for circumferential stem-turn-limiting engagement with the stop plate and the other being non-rotatably secured by the stop plate, and a locking edge on one of said plates engaged by a complementary face portion of the head when shifted axially by the spring.
